UNITED STATES PATENT OFFICE

144,221

DESIGN FOR A MAKE-UP HOOD OR SIMILAR ARTICLE

Marie Schaefer, New York, N. Y.

Application October 4, 1945, Serial No. 122,521

Term of patent 14 years

(Cl. D3—13)

To all whom it may concern:

Be it known that I, Marie Schaefer, a citizen of the United States of America, residing in New York, county of New York, and State of New York, have invented a new, original, and ornamental Design for a Make-up Hood or Similar Article, of which the following is a specification, reference being had to the accompanying drawing, forming part thereof.

Fig. 1 is a front perspective view of a make-up hood or similar article showing my new design.

Fig. 2 is a rear perspective view thereof.

I claim:

The ornamental design for a make-up hood or similar article, substantially as shown.

MARIE SCHAEFER.
